United States Patent Office

Des. 228,948
Patented Oct. 30, 1973

228,948

POCKET LEVEL

Maarten Cornelis de Jong, Canton, Conn., assignor to
The Stanley Works, New Britain, Conn.

Filed Nov. 8, 1971, Ser. No. 196,857

Term of patent 14 years

Int. Cl. D10—04

U.S. Cl. D52—6 A

FIG. 1

FIG. 4

FIG. 5

FIG. 2

FIG. 3

FIG. 1 is a top plan view of a pocket level showing my new design;

FIG. 2 is a side elevational view thereof, the opposite side being a mirror image thereto;

FIG. 3 is a bottom plan view thereof;

FIG. 4 is a left end elevational view thereof; and

FIG. 5 is a right end elevational view thereof.

I claim:

The ornamental design for a pocket level, as shown.
